UNITED STATES PATENT OFFICE

ARTURO LEVI, OF LONG ISLAND CITY, NEW YORK

DESIGN FOR A CIGARETTE LIGHTER

Application filed April 9, 1930. Serial No. 35,196. Term of patent 14 years.

To all whom it may concern:

Be it known that I, ARTURO LEVI, a citizen of the United States, and a resident of Long Island City, county of Queens, State of New York, have invented a new, original, and ornamental Design for a Cigarette Lighter, of which the following is a specification, reference being had to the accompanying drawing forming a part thereof.

In the drawing, the figure is a perspective view of a figure disclosing my new design.

I claim:

The ornamental design for a cigarette lighter as shown.

ARTURO LEVI.
